Attest:

UNITED STATES PATENT OFFICE

CHARLES E. PECKHAM, OF CHICAGO, ILLINOIS

RETAINING DEVICE

Application filed January 28, 1931. Serial No. 511,672.

This invention relates to retaining devices and more particularly to devices that may be used to hold articles of wearing apparel in proper position.

5 The salient objects of my invention are to provide a retaining device which may be used to hold an article such as a shirt in proper position to enhance the appearance thereof by preventing unwarranted wrinkling and the like; which will be comfortable so that it may be worn with ease; which will be adjustable in order that it may be neatly fitted on the body; and which will be detachable to facilitate installation and removal 10 thereof.

In the selected embodiment of my invention, illustrated in the accompanying drawing,

Fig. 1 is a front view showing my device 20 installed in position;

Fig. 2 is a side view;

Fig. 3 is a rear view;

Fig. 4 is a sectional view taken substantially on the line 4—4 on Fig. 1; and

25 Figs. 5 and 6 are perspective detail views of the parts of my device.

Referring to the drawing, 7 indicates a shirt including front tail portions 8 and 9, separated from each other at the front of the 30 shirt in the usual manner, and a rear tail portion 10 separated from the tail portions 8 and 9 by notches or gashes 11 and 12 formed in the material of the shirt. The front portions of the shirt are joined in the usual manner 35 as by buttons 13 and after the shirt has been put on my improved device is attached, and the purpose of this device is to hold the shirt somewhat taut about the shoulders and in the front and rear portions thereof to thereby 40 prevent unwarranted wrinkling thereof. In order that this may be attained my device is preferably made of elastic material and it consists of two parts respectively indicated by 14 and 15. The part 14 is preferably 45 made of greater length than the part 15 and

at the ends thereof pliable buttons 16 or the like are provided. These pliable buttons 16 are secured to rigid base sections 17 which may be made of metal, and these sections have slots 18 and 19 therein on each side of the 50 buttons 16. The end portion of the strip 14 is extended through the slot 18 and across the section 17 on the side thereof opposite the button 16 and then through the slot 19, after which the end portion of the strip 14 is looped 55 about the end of the section 17 so that it may be directed thereover, and the marginal portion of this end portion is folded upon itself and joined to the section of the portion 14 adjacent the opposite end of the section 17 by 60 stitching 20 or the like. The part 15 has a loop 21 fixed at one end thereof and the opposite end of the part 15 is folded upon itself and is connected to the usual slide retainer 22 mounted upon the section 15 and by moving 65 this slide retainer 22 along the section the length of the looped portion formed therein may be varied to thus vary the length of the part 15 to thereby provide an adjustment. In the bight of the looped portion a loop 23 70 is mounted and therefore loops are provided at opposite ends of the part 15. To install my improved device in position one end of the part 14 is extended below the tail section 10 adjacent either of the notches 11 or 75 12 and thus the buttons 16 will be covered by the cloth of the shirt. Then one of the loops, for example the loop 23, will be arranged in position to clamp the material of the shirt 80 between itself and the button 16 and therefore the parts 14 and 15 will be joined to the shirt. The part 14 will then be extended downwardly to pass about the rear and inner surfaces of the thigh of the person wearing the shirt and the opposite end portion of the 85 part 14 will be extended below either the tail portion 8 or the tail portion 9. The loop 21 will then be arranged in position to clamp the material of the shirt between this loop and the other button 16. The preferred manner 90

of carrying out this last connection is that the wearer of the shirt will stand upright and will pass the part 14 about the thigh, in the manner described, and under one of the front 5 tail portions. He will then stand upright and draw the shirt taut, after which he will grip the part 14 and the tail portion of the shirt to retain the button 16 in the proper location and then the loop 21 will be clamped in the 10 manner described. Since the parts are made of elastic material it is manifest that they will effectively retain the shirt substantially taut and therefore prevent unwarranted wrinkling thereof to thereby enhance the ap- 15 pearance. Since an adjustment is provided in the part 15 it is manifest that the retaining device may be adjusted to suit the needs of the particular person using the same, and while I have shown the adjustment as being 20 provided in the part 15 it is to be understood that it might be provided in the part 16 without departing from the purview of my invention. However, it is advantageous to provide an adjustment in the part 15 and I am 25 thereby enabled to provide a covering over the back of the base section 17 to thereby prevent its contacting with the body of the wearer. When it is desired to remove the shirt, the loops engaging the front tail por- 30 tions 8 and 9 are disengaged and therefore the shirt may be readily removed.

While I have illustrated and described a preferred form of construction of my invention, it is to be understood that this is 35 capable of variation and modification and I therefore do not wish to be limited to the precise details set forth but desire to avail myself of such changes and alterations as fall within the scope of the following claim.

40 I claim:

In a garment which has shoulder and trunk portions and front and rear tail portions at the lower end of the trunk portion with adjacent edges of the front and rear tail portions spaced from each other, the combination 45 therewith of a pair of elastic strips having connecting devices at corresponding ends thereof, said connecting devices being disposed adjacent the edges of the rear tail portions that are spaced from the front tail portions, said strips being extended over said front tail portions and having other connecting devices at the other ends thereof, another pair of elastic strips having connecting de- 50 vices at corresponding ends thereof, said last-named connecting devices being adapted to respectively cooperate with the first-named connecting devices to attach the rear tail portions to said connecting devices and to attach 55 the connecting devices together, said second-named elastic strips being extended over the inner sides of the thighs of the wearer of the garment and toward said other ends of the first-named strips and having connecting de- 60 vices at the ends thereof opposite the ends

connected to the first-named strips, these last-named connecting devices attaching the front tail portions to said other connecting devices on the first pair of strips and being attached to these other connecting devices whereby 70 said strips are connected into continuous loops, the strips acting to hold the shoulder portions of the garment snugly about the shoulders of the wearer and holding the trunk portion taut to prevent wrinkling 75 thereof.
